HINGE ASSEMBLY FOR FOCUSING GROUND
GLASS COVER

Henry O. Drotning and John D. Newell, Rochester, N. Y., assignors to Eastman Kodak Company, Rochester, N. Y., a corporation of New Jersey

Application February 2, 1939, Serial No. 254,260

6 Claims. (Cl. 95—44)

The present invention relates to a focusing ground glass cover for cameras or the like, and particularly to a hinge assembly for hinging such a cover to the ground glass support.

It is broadly old to provide a focusing ground glass with a hinge cover for alternately covering the same when not in use, and uncovering the same when it is desired to focus a camera; and the present invention is not concerned with such a structure broadly, but is directed to a hinge connection for a ground glass cover which has many advantages over the prior art. In known hinge connections of the type referred to, the hinge pins have been fixed in the ground glass support, as by screw threads, drive fits, etc., and the cover has been rotatably mounted thereon by having holes through which said pins would extend. It has been found, however, that where the ground glass support is so formed as to leave only a limited amount of stock into which the hinge pins are to be inserted, that a drive fit or screw-threaded attachment of the pins to the support very often breaks away the stock thus spoiling the entire piece. Further, when a ground glass support is molded, which is the cheapest manner of production, tapering side walls on the ground glass support result due to pattern making technique. Where a U-shaped cover is hinged to the ground glass support and the wings thereof overlap the side walls, means must be provided to eliminate frictional engagement between the wings and these tapered walls in order to prevent said wings from being sprung outwardly away from their normal position, or to prevent unnecessary frictional resistance to a hinging movement of the cover. The present invention overcomes these noted difficulties, and provides a hinge assembly which is cheap from both a manufacturing and an assembling standpoint.

One object of the invention is to provide a hinge assembly between a ground glass support and a ground glass cover in which the hinge pins are slidably inserted into hinge pin bores in the support, whereby limited amounts of stock will satisfactorily support the hinge pins. Another object is to provide a hinge assembly of the type described wherein the ground glass cover is mounted on the hinge pins by snapping the wings thereof over the ends of said pins to permit the same to engage holes in said wings, whereby the cover is held in assembled position on said pins due to the resiliency in the wings themselves, or the action of a resilient means tending to move the wings toward one another. A further object

is to provide said hinge pins with collars which, in addition to limiting the extent to which the pins can be inserted into said bores, also when engaged by said resilient wings of the cover, serve in combination with said wings to hold the pins in assembled position. And yet another object is to make the width of said collars on said hinge pins equal to the draft of the taper of the side walls in the ground glass support, whereby they also serve to space said wings from said side walls to eliminate frictional engagement between said wings and the side walls when the wings are moved to an overlapping position relative to the side walls. And another object is to provide means for positively limiting the hinging movement of the cover in its uncovering position when moved in that direction. And another, and one of the most important objects of the invention, is to provide a hinge assembly for the purpose pointed out which is cheap both from the manufacturing and assembling standpoints.

The novel features that we consider characteristic of our invention are set forth with particularity in the appended claims. The invention itself, however, both as to its organization, together with additional objects and advantages thereof, will best be understood from the following description of a specific embodiment when read in connection with the accompanying drawing in which:

Fig. 1 is a rear perspective view of a camera having an adapter back in place, which adapter back includes a focusing ground glass and cover therefor which are connected by a hinge assembly according to the present invention.

Fig. 2 is a section taken transversely of the adapter back, and through the ground glass support, and showing the ground glass cover in a raised or uncovering position.

Fig. 3 is a top plan view of the ground glass support exclusive of the adapter back, and with the cover raised.

Fig. 4 is a section taken substantially on line 4—4 of Fig. 3.

Fig. 5 is a side elevation of the ground glass support with the cover raised, and with a part of the cover broken away to show the spring finger for frictionally engaging and retarding movement of the same, and,

Fig. 6 is an enlarged detailed elevation of one corner of the ground glass support minus the cover, and showing the limited amount of stock provided in which the bore for the hinge pin must be made.

Like reference characters refer to corresponding parts throughout the drawing.

Although the novel hinge assembly is shown and described herein as applied to a particular ground glass support, one for use with which it was particularly designed, it is to be understood that it could be used with any ground glass support having a hinge cover, regardless of the shape or character of said ground glass support.

10 Cameras of the film pack or plate type, e. g., Recomar Camera, are usually made to take comparatively large pictures, i. e., $2\frac{1}{4} \times 3\frac{1}{4}$, or $3\frac{1}{4} \times 4\frac{1}{4}$, and the plates or film packs are removable from the camera back to be replaced by a 15 focusing ground glass which can be slid into the place of the films for focusing purposes. In answer to a demand by the owners of cameras of this type to be able to use the miniature roll films, particularly color films, an adapter back has been 20 provided which can be slipped onto the camera in place of the regular film pack or plate, and which adapter back provides for the use of these miniature films along with ground glass focusing. It is in connection with such an adapter back that 25 the present invention is disclosed merely because it was particularly designed for use on the same, and not because it is limited to use therewith.

Referring to Fig. 1 a plate or film pack camera is shown with a miniature roll film adapter back 30 placed thereon, said adapter back including a focusing ground glass which is shown in its operative position with the cover thereof raised. A camera of this type may include a camera body 19 along each longitudinal edge of the back wall 35 of which is located runners 11 which ordinarily guide the film pack, plate, or ground glass into the focal plane of the camera lens when slid thereinto. The miniature film adapter back includes a mounting plate 12 which can be slid onto 40 the camera back in engagement with the runners 11 after the ground glass, film pack or plate has been removed from said back. This mounting plate 12 may be releasably held in position by the pivoted latch 13 on the camera body, which latch 45 also serves to hold the film pack or the like in place on the camera back. On the mounting plate 12 are fixed a pair of spaced undercut guides 14 which slidably engage undercut flanges 15 on the base member 16, see Fig. 2, to permit said 50 base member to be slid longitudinally of said mounting plate 12.

This base member 16 includes an upstanding ground glass support and an upstanding camera support, indicated generally as 17 and 18 respectively, and which are spaced apart on the base member as shown in Fig. 5. On the top of the ground glass support 17 there is mounted a ground glass 19 for focusing purposes, and which ground glass is adapted to be covered or uncovered by 55 a hinge cover member indicated generally as 20. On the camera support 18 is mounted the camera body 21 of a miniature camera which serves merely as a roll film support and a film advancing means. Those skilled in the art will appreciate that the miniature camera body 21 is minus the usual lens or bellows, the lens and bellows of a plate camera being used for exposing the film in the miniature camera body. When the base member 16 is slid in one direction on the mounting plate 12 the ground glass 19 will be moved over 60 an exposure aperture, not shown, in the mounting plate 12 which corresponds in size to the miniature film in the camera body 21, for focusing and composing pictures. After focusing is completed 65 the base member is slid in the other direction on

the mounting plate 12 to bring the camera body 21 over the exposure aperture in the mounting plate whereupon an exposure can be made on the film therein. The film is advanced through the camera body 21 by a rotating winding knob 5 22 thereon, as is well known, and in mounting the camera body 21 and the ground glass 19 on their respective supports 18 and 17 it is assured that the two will be in the same plane. To insure the film or ground glass of the adapter back being 10 accurately located in alignment with the exposure aperture of the mounting plate 12, and locked in said position without attention of the operator, a pair of perforated spring catches 23 and 23' are mounted on the guides 14 to extend over said 15 mounting plate 12 and into the path of the base member 16. Each of these catches engages pins 24 or 24' extending upwardly from the base member 16, when the pin is moved thereunder, and these catches are so spaced from one another longitudinally of the guides 14 that one serves to hold the base member in focusing position on the mounting plate 12, while the other holds the base member in exposing position on the mounting plate. 25

The above described adapter back as a whole forms no part of the present invention, but is merely disclosed to show one specific application of our novel hinge assembly between the ground glass support and the ground glass cover thereon. It is such an application that the novel hinge assembly was designed for, and it clearly illustrates the advantages of such an assembly. 30

Referring now particularly to Figs. 2-6, which shows the hinge assembly for the ground glass cover, or the present invention, in detail, the base member 16 is provided with an aperture 28 which is adapted to be brought over the exposure aperture in the mounting plate 12 for focusing purposes; and the base member 16 includes upstanding side, back, and front walls 29, 30, and 31 respectively which surround said aperture 28 and form a ground glass support. The top of the side walls 29, and approximately half of the top of the front and back walls 30 and 31 are cut down to provide a seat in which the ground glass 19 is seated, and said ground glass is firmly held in place by a metal frame 32 covering the edges of said ground glass and which frame is fastened to said side walls by screws 33. It will be readily appreciated that the top of the side, front, and back walls of the ground glass support are cut away as described to permit the top of the metal frame 19 to remain below, or be flush with, the top of the walls so that the cover can close as hereinafter described. 50

Referring to Figs. 3, 5, and 6, it will be noticed that cutting half of the front and back walls away to form a ground glass seat in effect leaves 60 two narrow rails, which will be designated by 34, extending the length of said walls. The rail on the back wall provides the stock into which the hinge pins for the cover are to be mounted, and although they are hardly wide enough for 65 this purpose, their width is limited due to the fact that a space must be left between the ground glass support 17 and the camera support 18 wide enough to receive the side wall of the camera body 21, see Fig. 5. It was found that due to the limited amount of stock which the rails 34 provided, that if the hinge pins were screwed into tapped holes in the end of the rear rail 34, or had a drive fit with a smooth bore therein, as is generally done, that portion of the rail adjacent the 70

hinge pin hole would very often break away, thus spoiling the entire base member.

Our novel hinge assembly overcomes this difficulty by providing each end of the rear rail 34 with a hinge bore 35 extending longitudinally of the rail whereby the rail constitutes the hinge axis. Into each of these hinge pin bores 35 is slidably inserted a hinge pin 37, the diameter of which is such that it can be slid into or out of the hinge pin bores easily and without inducing a pressure on the walls of the bore, which pressure would tend to rupture the walls of the bore and break away the rail. We have found that by inserting a hinge pin in the rail 34 in this manner that no breaking away of the rail is encountered.

Each hinge pin 37 is provided intermediate its ends with an enlarged collar 38 which engages the end of the rail 34, and which may serve to limit the extent to which the hinge pin 37 can be inserted into its bore 35 should the depth of the bore be greater than the length of the hinge pin from the collar to its end, as shown in Fig. 4.

The ground glass cover 20 may be substantially 25 U-shaped, having a top portion 39 covering said ground glass proper, and wings 40 for shielding the stray light from the sides of the ground glass when the cover is raised. Each of the wings 40 is provided with a hole 41 which is 30 adapted to snap over the end of the hinge pin extending beyond the side walls 29 so as to rotatably hinge the cover to the ground glass support. The cover is preferably made of thin metal so that the wings 40 integral therewith will have 35 a resiliency inherent in the metal itself, and can be sprung toward or away from each other. These wings are purposely initially sprung so that they will normally incline a slight amount toward each other, and the distance between said 40 two wings should be less than the distance between the outside ends of each of the hinge pins. In order to mount the cover 20 on the hinge pins 37 the wings 40 must be sprung outward to snap 45 the holes 41 therein over the ends of said hinge pins, whereafter the wings will spring back to their normal positions and by engaging the outside of the collars 38 on each pin will serve through their normal resiliency to hold said pin, as well as the cover itself, in assembled position.

50 Although we have shown a cover made of thin metal with the wings integral therewith to provide the desired resiliency for the wings, it is to be understood that other constructions, although not as simple, could be made to give this 55 desired flexing action to the wings. Such a modified arrangement might include a cover having the wings hinged to the top portion and normally spring pressed toward one another by springs at the hinge axis of the wings and top portion. Therefore, it is pointed out that the invention is not limited to the use of a cover constructed as disclosed, but any cover having the wings arranged so as to be capable of movement toward and away from one another, and normally moved toward one another, would suffice.

For cheapness of manufacture, the base member 16 is generally molded, and due to pattern making technique this necessitates that the outside surface of the side walls 29 taper outwardly 70 from the top to the bottom thereof, see Fig. 2. In order to prevent the wings 40 from frictionally engaging these tapered side walls 29 when moved to a covering position, wherein the wings overlap the side wall, the width of each collar 38 75 on each hinge pin 37 is made equal, or substan-

tially so, to the draft of the side wall taper. Thus, the collar in addition to its other enumerated functions, spaces the wings 40 away from the side walls so that in moving to an overlapping position relative thereto they will not engage said 5 side walls at all or, if at all, only at the bottom of the taper. These collars, therefore, prevent undue frictional resistance between the cover and the side walls, and a consequent outward springing of the wings 40, and perhaps accidental dis- 10 assembling, both of which would result if, when the cover was moved to its closed position, the wings were not spaced from said side walls to accommodate for said taper.

In order to provide a slight frictional control 15 or resistance on the cover to prevent an uncontrolled flopping thereof, and to provide means for positively stopping the same in its raised position when moved there-toward, the following structure is provided. A spring finger 43 formed integral with the ground glass frame 32 is adapted to overhang one of the side walls 29 and extend outward therefrom and into frictional engagement with one of the wings 40. This spring finger has just enough resiliency to retard, not 25 hamper, movement of the cover when frictionally engaging the wings. The lower corner of the wing 40 engaged by said spring finger 43 is provided with an inturned lug 44 which engages said spring finger when the cover is fully raised and 30 positively limits further hinging movement in this direction.

From the foregoing disclosure it will be appreciated that our novel hinge assembly possesses several advantages over the prior art. First 35 a hinge assembly is provided which is extremely simple and which is cheap from a manufacturing standpoint. This hinge assembly can be rapidly and easily assembled by an unskilled workman, because of the fact that all of the parts are held in their respective assembled positions due to the formation of the parts and the physical characteristics inherent in or built thereinto. The particular formation of the hinge pin provides three separate and distinct 40 functions. First, the collar on the pin serves to limit the extent to which the pin can be slid into its hinge pin bore. Secondly, the collar in combination with the resilient characteristic of the wings insures the hinge pins being held in 45 their assembled positions without benefit of an attaching means. And thirdly, the collar accounts for the taper of the side walls of the ground glass support and eliminates, or reduces, the frictional resistance which would ordinarily 50 be encountered between the side walls and the wings of the cover, were said wings not spaced from said side walls. In addition, the disclosed hinge assembly can be satisfactorily used where 55 a limited amount of stock is allowed for seating hinge pins, this being a result which could not be realized or accomplished by known hinge assemblies where it is necessary to attach the hinge pins to one of the hinge members by a screw threaded engagement, a drive fit, or the 60 like.

Having thus described our invention, what we claim is new and desire to secure by Letters Patent of the United States is:

1. A hinge assembly comprising a base member 70 provided with a viewing aperture and having side walls, one of which is provided with a hinge pin bore, a cover for covering said aperture, and having a pair of spaced wings normally urged toward each other for overlapping the side 75

- walls of said base member, each of said wings provided with a hole, and a hinge connection including a hinge pin extending from each of said side walls, one of said hinge pins adapted to be slidably inserted into said bore, said hinge pins spaced apart along the hinge axis whereby their outer ends are adapted to be spaced apart a distance greater than the spacing of said wings, and a collar on the slidably inserted hinge pin, located to be engaged by a wing of said cover, when the holes therein are snapped over the ends of said hinge pins, and normally held thereby with said hinge pin in its hinge pin bore.
2. A hinge assembly comprising a base member provided with a viewing aperture and having side walls each provided with a hinge pin bore, a cover for covering said aperture, and including a pair of spaced wings normally urged toward each other for overlapping the side walls of said base member, each of said wings provided with a hole, and a hinge connection including a pair of hinge pins one of which is slidably inserted into each of said bores, and spaced apart along the hinge axis whereby their outer ends are adapted to be spaced apart a distance greater than the spacing of said wings, and a collar on each of said hinge pins, located to be engaged by a wing of said cover, when said holes therein are snapped over the ends of said hinge pins, and normally held thereby with said hinge pin in its hinge pin bore.
3. A hinge assembly comprising a molded base member provided with a viewing aperture, and having tapering side walls one of which is provided with a hinge pin bore, a cover for covering said aperture and having a pair of spaced wings normally urged toward each other for overlapping the side walls of said base member, each of said wings provided with a hole, a hinge connection including a hinge pin extending from each of said side walls, one of said hinge pins adapted to be slidably inserted into said bore, said hinge pins spaced apart along the hinge axis whereby their outer ends are adapted to be spaced apart a distance greater than the spacing of said wings, and a collar on each of said hinge pins, located to be engaged by a wing of said cover when the same is snapped over said pins to engage the holes therein, said collars being equal in width to the draft of the taper of said side walls, whereby the wings in overlapping said side walls do not engage said side walls so as to be sprung apart by such engagement.
4. A hinge assembly comprising a molded base member provided with a viewing aperture, and having tapering side walls each provided with a hinge pin bore, a cover made of resilient material for covering said aperture and including a pair of spaced wings normally urged toward each other from the vertical due to the resiliency of the material from which the cover is fabricated, and adapted to overlap the side walls of said base member, each of said wings provided with a hole, a hinge connection including a pair of hinge pins, one of which is slidably inserted into each of said bores, and spaced along the hinge axis whereby their outer ends are adapted to be spaced apart a distance greater than the spacing of said wings, and a collar on each of said hinge pins, located to be engaged by a wing when the same is snapped over the end of said pin and the pin extends through said hole therein, whereby each of said pins is held in said bores by the normal resiliency of said wings, said col-

lar being equal in width to the draft of the taper of said side walls, whereby the wings in overlapping said side walls do not engage the same to be sprung apart.

5. In an apparatus of the type described a hinge assembly comprising a molded ground glass support rectangular in shape provided with a viewing aperture, and having upstanding and tapering side walls, a rail extending across the top of two parallel side walls, the opposite ends of one rail each provided with a hinge pin bore, a ground glass located over said viewing aperture and between said rails, a metal cover for covering said ground glass, and including a pair of spaced wings normally urged toward each other from the vertical due to the resiliency of the metal for overlapping the side walls of said ground glass support, each of said wings provided with a hole, a hinge connection between said support and said cover including a pair of hinge pins, one of which is slidably inserted into each of said bores, and spaced apart along the hinge axis whereby their outer ends are adapted to be spaced apart a distance greater than the spacing of said wings, and a collar on each of said hinge pins located to be engaged by a wing when the same is snapped over the end of the pin and the pin extends through said hole therein, said collar being equal in width to the draft of the side wall taper, whereby the wings are spaced from said side walls so as not to engage the same when moved to an overlapping position relative thereto.

6. In an apparatus of the type described a hinge assembly comprising a molded ground glass support rectangular in shape provided with a viewing aperture, and having upstanding and tapering side walls, a rail extending across the top of two parallel side walls, the opposite ends of one rail each provided with a hinge pin bore, a ground glass located over said viewing aperture and between said rails, a metal frame for holding said ground glass in place over said aperture, a U-shaped metal cover for covering said ground glass the wings of which are normally urged toward each other from the vertical due to the resiliency of the metal and adapted to overlap the side walls of said ground glass support, each of said wings provided with a hole, a hinge connection between said support and said cover including a pair of hinge pins slidably inserted into said bores, and spaced apart along the hinge axis whereby their outer ends are adapted to be spaced apart a distance greater than the spacing of said wings, a collar on each of said hinge pins located to be engaged by a wing when the same is snapped over the end of the pin to engage the same in the hole in said wing, said collar being equal in width to the draft of the side wall taper whereby the wings are spaced from said side walls so as not to engage the same when moved to an overlapping position relative thereto, a resilient finger integral with said ground glass frame and extending beyond one tapering side wall to engage one of said wings for frictionally retarding a hinging movement of said cover, and a lug on the wing engaged by said resilient finger adapted to positively engage said spring finger when said cover is moved to its uncovering position for providing a positive stop.

HENRY O. DROTNING.
